UNITED STATES PATENT OFFICE.

JOSEPH LUSSE AND ROBERT LUSSE, OF PHILADELPHIA, PENNSYLVANIA, ASSIGNORS TO LUSSE BROTHERS, OF PHILADELPHIA, PENNSYLVANIA, A PARTNERSHIP CONSISTING OF JOSEPH LUSSE AND ROBERT LUSSE, BOTH OF PHILADELPHIA, PENNSYLVANIA.

DESIGN FOR AN AMUSEMENT CAR.

Application filed July 10, 1923. Serial No. 6,749. Term of patent 7 years.

To all whom it may concern:

Be it known that we, JOSEPH LUSSE and ROBERT LUSSE, citizens of the United States, residing in Philadelphia, Pennsylvania, have invented a new, original, and ornamental Design for an Amusement Car, of which the following is a specification, reference being had to the accompanying drawing, forming part thereof, in which the figure is a perspective view of an amusement car, showing my new design.

We claim:

The ornamental design for an amusement car, substantially as shown.

JOSEPH LUSSE.
ROBERT LUSSE.
